DISPENSING DEVICE FOR FILLING GREASE
GUNS AND THE LIKE

Edwin P. Sundholm, Albert City, Iowa

Application October 21, 1938, Serial No. 236,281

26 Claims. (Cl. 221—47.5)

The present invention relates to a gun-filling dispensing-container for use as an original vendable-package unit for more or less viscous fluids such as the various grades of greases or the like, whereby, more or less viscous fluids may be more readily and more efficiently dispensed from the original vendable container unit, and the present invention relates more particularly to dispensing containers for shipping and/or storing relatively large supplies (that is, 10, 25, 40, 50, 75, 100 or more pounds) of grease or similar more or less viscous fluids, and having means whereby, and being so arranged that the viscous-fluid content of such dispensing-container may be filled or dispensed directly into the tubular reservoirs or so-called "barrels" of grease guns and like applicators used for the ultimate distribution and dispensing of greases or other viscous fluids, without the necessity of ladling out or otherwise first removing the grease from the dispensing-container by extraneous means; the tubular reservoir or so-called "barrel" of the conventional grease gun or like applicator or ultimate dispenser being used directly for withdrawing the grease or other viscous-fluid content of the dispensing-container of the present invention by means of suction created within such conventional "barrel," which suction serves to effect or to stimulate or accentuate the flow of the viscous-fluid content of the dispensing-container of the present invention.

One of the difficulties long experienced in filling grease guns with grease from original containers, such as drums or buckets, is that the lid of such grease-drum or grease-bucket must first be removed in order to give access to the grease, and the lid is frequently not replaced on the drum or bucket and often cannot be replaced so as to exclude dirt, because in prying the lid off the drum the rim of the lid is generally damaged and distorted. These grease-drums or grease-buckets are used in garages, farms and places where all kinds of foreign matter, such as leaves, dirt, grit and dirty water frequently get into the drum or bucket and on top of the grease. One customary way of filling grease guns has been to ladle or scoop out the grease with a paddle of wood or the like and then ladle it into the grease-gun "barrel" with a similar manual operation; while another customary way of filling grease guns has been to submerge the end of the cylindrical grease-reservoir or so-called "barrel" of the grease gun into the drum or bucket of grease and then to pull the rod or handle of the grease-gun follower-piston back so as to suck the grease into

the grease-gun barrel as in Patent No. 1,377,023. This type of operation has a dual effect of carrying dirt into the grease-drum or grease-bucket and also of getting the grease-gun reservoir or "barrel" smeared with grease on the outside.

One of the objects of the present invention is to eliminate the above noted objections by providing an original vendable grease-dispensing container on which the lid may be left substantially intact, without ever disturbing the same, so that no foreign matter can get into the grease and so that only fresh and clean grease can be furnished to the grease gun, so that the grease gun itself may not become foul or rendered inoperative by dirty and grit-contaminated grease.

Another object of the present invention is to provide a grease container, which may indeed be the original container or package in which the grease is shipped and sold, or which may be an intermediate container into which the grease is placed from the original package, and which (container of my present invention) is so arranged that the grease may be covered at all times so as to keep it clean, and that it may be withdrawn from time to time in relatively smaller quantities directly into the grease reservoir portion or "barrel" of the conventional grease gun or the like without the necessity of separately handling the grease.

A further object of the present invention is to provide a grease container of the character stated from which substantially all the grease may be completely removed so that there is no waste of grease.

A further object of the present invention is to provide a grease container to which the generally cylindrical grease reservoir or "barrel" of the conventional grease guns may be screw-threadedly or otherwise detachably secured in a quick and easy manner, so that by withdrawing the follower piston in said grease reservoir or "barrel" of the conventional grease gun, said grease reservoir or "barrel" will be completely filled with a fresh supply of grease from the container forming the subject matter of the present invention.

With the above and other objects in view, one phase of the present invention consists of a generally upright and preferably cylindrical dispensing container formed of sheet-metal or other thin, form-retaining sheet material and capable of containing a substantial quantity of grease or other more or less viscous fluid, as for instance, 10, 25, 50, or 100 pounds or more, and preferably having a freely floating piston-like follower-plate therein adapted to rest on the top of the body of

the viscous fluid and to ride downwardly on the top surface of the fluid, a suction-receiving socket on the outside of said container near the bottom thereof for telescopically receiving the intake or 5 suctional end of the cylindrical reservoir or "barrel" of the conventional type grease gun or like applicator or ultimate dispenser and for making a fluid-seal therewith, an aperture in the bottom of the container and a conduit communicating with said aperture and said socket for conveying the fluid from said container to said socket, and means for spacing the bottom of said container above the floor level or supporting surface upon which the container is to rest, sufficiently to clear said passageway and said suction-receiving socket.

Another phase of the present invention also consists of certain novel principles, features and details of construction, in a viscous-fluid dispensing container of the kind indicated, whereby the 20 objectives hereinabove set forth may be attained in a practical, durable and efficient form at a cost low enough to permit the wide and general use of such fluid-dispensing container as an original 25 "single-trip" container, namely, one which the manufacturer or supplier of grease can afford to use without materially increasing his grease price and without having to take back the emptied container from his vendees for refund.

30 The present invention may further include certain other novel features and details of construction, all of which will appear more fully from the following detailed description and accompanying drawings.

35 For the purpose of illustrating the invention, there are shown in the accompanying drawings forms thereof which are at present preferred, since the same have been found in practice to give satisfactory and reliable results, although it 40 is to be understood that the various instrumentalities of which the invention consists can be variously arranged and organized and that the invention is not limited to the precise arrangement and organization of the instrumentalities as herein shown and described.

45 Referring to the drawings in which like reference characters indicate like parts,

Figure 1 represents a sectional view of a grease dispensing container constituting one embodiment of the present invention; having the fluid-receiving end of a conventional grease reservoir or "barrel" of a grease gun operatively inserted 50 into the suction-receiving socket thereof.

Figure 2 represents a section generally on line 55 2-2 of Figure 1.

Figure 3 represents a section generally on line 3-3 of Figure 1.

Figure 4 represents a section similar to that shown in Figure 2 illustrating a modified form of 60 construction embodying the present invention.

Figure 5 represents a fragmentary section on line 5-5 of Figure 4.

Figure 6 represents a fragmentary section of one form of construction for the attachment of 65 the gun-receiving socket to the side-wall of the lubricant-reservoir, illustrating a further modified form of construction in respect to this phase.

Figure 7 represents a fragmentary section on line 7-7 of Figure 4 illustrating a further alternative form of construction embodying the present invention, wherein a weak leaf-spring type check-valve is placed beneath the central opening in the bottom to restrain free flow of grease when the device is not being actually operated.

75 Figure 8 represents a vertical section of the

grease dispensing device embodying the present invention, showing a still further modified form of construction in the internal shut-off phase of the invention.

Figure 9 represents a fragmentary view of a gun-receiving socket taken generally in the direction of the arrows 9-9 shown on Figure 4, illustrating a further modified form of construction in the shut-off phase of the present invention.

Figure 10 represents a fragmentary cross-sectional view similar to that shown in Figure 7, illustrating, however, an upwardly inclined gun-receiving socket and also showing, in cross-section, the form of shut-off illustrated in Figure 9.

Figure 11 represents another modified form of grease-dispensing device embodying the present invention, including an outwardly flared upper zone on the cylindrical body of the grease-dispensing container and showing a modified form 20 of follower plate.

Figure 12 represents a top plan view of a follower plate of a modified form of construction.

Figure 13 represents a side elevational view of the same.

Figure 14 represents a top plan view of a follower plate of still another modified form of construction.

Figure 15 represents a side elevational view of the same.

Figure 16 represents a perspective view of a gun adapter.

Figure 17 represents a cross-sectional view of another form of gun adapter.

Figure 18 represents a top plan view of a 35 grease-dispensing container embodying the present invention, but showing a modified form of construction, with a part of the plate over the bottom passageway broken away.

Figure 19 represents a front elevational view 40 of the same with the top part of the device broken away.

Figure 20 represents a fragmentary section on line 20-20 of Figure 19, on an enlarged scale.

Figure 21 represents a section on line 21-21 of 45 Figure 19, on an enlarged scale.

Figure 22 represents a fragmentary section on line 22-22 of Figure 18.

Figure 23 represents a section of a modified form of adapter.

The grease-dispensing container of the present invention is particularly intended for use in filling the small portable type grease guns now generally used, that is, the type which may be carried about in the hand of the operator while in use, and more particularly, for use with the type of grease gun (either manually actuated or pneumatically or electrically actuated) in which the generally cylindrical grease reservoir or so-called "barrel" of the grease gun has within it a follower-piston and in which said cylindrical grease-reservoir or "barrel" is refilled from time to time by unscrewing or otherwise detaching from it the high-pressure pump portion of the grease gun (which is sometimes referred to as the "head" or high-pressure "head" of the grease gun) and then submerging the thus opened end or free end of the barrel of the grease gun into a supply of grease and then manually withdrawing the follower-piston in said gun barrel by a suitable piston-rod or pull rod or chain so as to suck said gun barrel full of grease. Grease guns of this general type may be exemplified by the grease guns shown in

1,587,597, 1,692,423, 1,696,606, 1,619,126, 1,377,023, 1,790,914, 1,894,274, and 1,926,398.

The grease-dispensing container of the present invention includes a generally cylindrical body 5 of suitable diameter and height to provide the desired volumetric capacity, and a bottom 6 having an opening 7 preferably centrally thereof. For instance, for an effective twenty-five pound capacity the diameter of ten inches and a height 10 of twelve inches is suitable, and so on.

The entire container may be formed of sheet metal, preferably suitable sheet steel such as is used for steel drums, and of a suitable gauge according to the size of the container. The thicknesses shown in the drawings are exaggerated for purposes of more ready illustration. Other thin form-retaining sheet-materials may be used.

The bottom 6 is preferably formed with a flange 8 of suitable depth to clear the lateral conduit 9 and gun-receiving socket 10 which will be described more fully hereinafter, thus forming a downwardly cupped member or inverted cup-shaped member. The flange 8 of the inverted cup-like bottom is of an external diameter such 25 as to telescope into the lower end of the cylindrical body 5 and is preferably drawn from the same sheet of metal as that of which the bottom 6 is formed, as for instance, by being drawn in a die on a suitable press, or by any other suitable 30 drawing or forming operation. The flange 8 is then turned and folded and crimped or "double-seamed" along with the lower peripheral edge of the cylindrical body 5, to form a crimped and interlapping bead-like seam or "double-seam" 11 35 with the lower peripheral edge of the cylindrical body 5, which seam thus unites the flange 8 with the corresponding lower portion of the cylindrical body 5, and which, at the same time, secures the bottom 6 permanently in place in fluid-sealed relation to the body 5. The bottom 6 may also be 40 held in place in a raised position by other means, as for instance, by welding it in place to the sidewall of the body 5 or by forming an outwardly pressed slight annular or peripheral groove in the body 5 at a suitable height above the lower extremity thereof into which the outer marginal portion of the bottom 6 may extend, to be held in 45 place thereby. Likewise, the bottom 6 may have but a short downwardly extending flange which 50 may be spot-welded to the side of the body 5.

The generally upright body 5 need not necessarily be cylindrical in shape or circular in horizontal cross-section, but may also be polygonal in horizontal cross-section, although the generally 55 cylindrical form is preferable.

The portion of the body 5 which is below the bottom 6 need not be continuous in its circumference, but may be cut out in parts to form a discontinuous lower extremity. Thus, for instance, three, four or more portions of the body 60 5 may be left projecting below the bottom 6 for the purpose of spacing the bottom 6 at a suitable distance above the lower extremity of the body.

The transverse conduit 9 may be formed by 65 welding, spot-welding or otherwise securing it to the undersurface of the bottom 6, in communication with the opening 7 therein, so as to form a continuous but enclosed passageway communicating with the interior of the container through 70 the opening 7 and extending to the flange 8 of the bottom. Openings 12 and 13 may be extended through the flange 8 and through the cylindrical body 5 of the container in registration or general alignment with the cross-section of the 75 conduit 9, so as to form a passageway in con-

tinuation thereof. To the outside surface of the cylindrical body 5 of the container, the gun-receiving socket 10 is secured, also having a similar opening 14 in registration or general alignment with the openings 12 and 13 and with the conduit 9. The socket 10 is provided with a generally cylindrical flange 15 which is adapted teleoscopically to receive (either internally or externally) the suctional end of a suction-filling "barrel" of an ultimate fluid-dispenser, and may 10 be internally screw-threaded as indicated at 16, to receive the externally screw-threaded ends 17 of the cylindrical reservoirs or "barrels" 18 of conventional grease guns or the like, or may be externally threaded or may be provided with 15 bayonet catch.

Within the cylindrical body 5 of the dispensing-container of the present invention, a freely floating piston-like follower plate 19 is provided in operative relation to the interior diameter of said 20 cylindrical body 5. The follower may be provided with an upturned flange 20 of suitable axial depth to afford some (more or less) guidance to the follower 19 so as to tend to prevent angularity 25 or "cocking."

By making the upturned flange 20 comparatively slight, or by fitting the follower 19 in the cylindrical body 5 with a substantial clearance, or by both, the free-floating follower-plate 19 can be given full freedom for tilting or "cocking." 30 By so arranging the follower-plate in relation to the cylindrical body or reservoir 5, as to permit free "cocking" or tilting, the follower-plate may tilt to a suitable extent as it rests and floats on top of the body of grease, so that if the container or reservoir wall 5 should become dented in shipping or handling, or in storage or in actual use, any slight dent will not "jam" the follower-plate and will not prevent the follower-plate from 35 traveling down to the bottom of the container. 40 Thus, when one part of the periphery of the follower-plate is obstructed or engaged by an inward dent in the reservoir wall, the part of the follower-plate which is so engaged is held in place temporarily by the dent in the wall, while the diametrically opposite part of the plate follows down with the grease body; which grease body thereby 45 temporarily acquires a slanting upper surface. This tilting of the follower-plate, and the corresponding inclination of the upper surface of 50 the grease continues as the body of grease is gradually exhausted or withdrawn, until the minor axis of the (then elliptical) vertical projection of the thus inclined follower-plate becomes less than the horizontal diametral distance across the container at the point of maximum indentation. When this inclination is 55 reached, the engaged peripheral point of the follower-plate will gradually pass by the indentation in the reservoir or container wall. After it has so passed the indentation, the follower-plate will again straighten out into a horizontal position, because of the natural tendency of the more or 60 less viscous fluid body to level out under the force of gravity.

Radial reinforcing ribs 21 may be pressed into the follower 19 so as to stiffen the follower plate 19. The ribs 21 are preferably decreased in height from the center towards the periphery as indicated in Figure 1. Three, four or more such radial ribs may be provided; four being indicated in the drawing of Figure 1. Any suitable (conventional) handle may also be provided on the follower 19 for readily raising the follower out of 65 70 75

the container if it is desired to refill the container after it has been completely exhausted.

- 5 A lid 22 either fitting loosely over, or more or less frictionally telescoped into the top or over the top of the body 5 is also preferably provided for generally excluding dirt and water from within the container. The lid 22 may also be crimped or otherwise affixed to the upper end of the cylindrical body 5. The lid 22 is preferably provided with a screw-threaded vent hole into which a screw 24 may be threaded. The lid 22 may also be provided with a central raised portion 23 which is pressed out of the sheet-metal of the lid and in which the vent hole is placed for receiving the screw 24. By removing or partly raising the screw 24, a vent is provided at the top through which air may enter at the top of the container as grease is withdrawn from the bottom of the container, so as always to maintain normal atmospheric pressure within the container. The upper periphery of the body 5 may also be suitable beaded or flared as indicated at 25, thereby to reinforce or stiffen the upper periphery of the container.
- 10 25 By raising the central portion of the lid 23, any rain or water which may tend to collect on the top of the lid 22 is diverted from the vent opening in the top of the container so as to be excluded from the interior of the container.
- 15 30 If desired, the transverse bottom conduit 9, may also be formed by pressing suitable channel-shaped depression 26 out of the bottom 6 of the device, but integrally therewith, and then superimposing a flat plate 27 over said depression 26 and spot-welding it, fusing it, soldering it, or otherwise securing it to the bottom 6 along the marginal zone around the depression 26. In this form of construction, the flat plate 27 may contain the central opening 7 as indicated in Figures 4, 5, 7 and 8, or the opening may be located off center but spaced inwardly from the side-wall 5 of the device.
- 20 35 The transverse cross-sectional or effective area of the conduits 9 (Figures 1, 3, 5, 8, 11 and 19) is substantially less than the cross-sectional area of the gun-receiving portions of the sockets 10 and 65 and is preferably of a relatively shallow cross-sectional contour. The reduced cross-sectional area and the length of the conduits 9, 40 afford suitable resistance to the flow of fluid, so as to prevent, or to slow down the free flow of grease when the gun barrel 18 is removed from the gun-receiving socket. This resistance to flow will either eliminate all free flow or will minimize it to such an extent as to permit the leisurely insertion of the plugs 40 or 73 into the gun-receiving sockets 10 or 65 after the gun barrel 18 has been removed, without any undue dripping or loss of grease. Thus, by reducing the cross-sectional area of the conduit 9 substantially below the cross-sectional area of the gun-receiving portion of the socket, and indeed substantially below one-half of the cross-sectional area of the socket 45 as indicated particularly in Figures 3, 5, and 9, resistance is interposed to the free flow of the normally viscous grease. This reduction in cross-sectional area may then further be augmented and accentuated by the length of the conduit.
- 50 55 60 65 70 75 By also making the passageways or conduits 9 generally flat or of generally non-circular cross-section, and preferably asymmetric with respect to the gun-receiving socket, as indicated in Figures 3, 5, 19 and 22, the surface friction exerted upon the grease in the passageway 9 is further

increased above that afforded by a passageway of circular cross-sectional area because the surface presented to the grease (per unit of length traversed by a given volume of grease) is thereby increased above that presented by a passageway of 5 circular cross-section.

By the foregoing means, resisting the free flow of grease, some of the types and kinds of greases generally and widely used can be effectively controlled in the manner hereinabove indicated, 10 under normal climatic conditions, without resorting to the more positive shut-off means hereinafter described and shown in Figures 8, 9 and 10.

The socket 10 may either be of cast metal or it 15 may be pressed sheet-metal, formed by customary and suitable stamping or die-forming operations. In Figures 4, 6, 7, 8, 10, 18, 19, 20 and 21, the socket is shown as being formed of sheet metal, although, as stated, these sockets may also be 20 formed of cast metal or other material.

Any of the sockets 10 may be turned upwardly at any suitable angle as indicated in Figure 10, so that the cylindrical grease reservoir or "barrel" 18 of the conventional grease gun may be applied thereto more conveniently by the operator, particularly in the case where the dispensing device of the present invention may be of a large size which would normally stand on the floor, although this upturned socket may also be used 30 on smaller devices embodying the present invention.

The socket 10 may be applied to the cylindrical body 5 by a crimped sealing junction by means of a generally annular eyelet or grommet 28 35 clamped or crimped over around the aligned openings 13 and 14 in the cylindrical wall 5 and in the bottom of the socket 10, as indicated more particularly in Figure 6. An inner member 29 may serve to provide a flat seat for the resilient 40 sealing gasket 30.

In Figure 8, a form of construction is shown in which a valve disc 31 is provided over the bottom opening 7. The shut-off disc 31 may be carried by a vertical rod 32 and may be welded thereto 45 as indicated at 33. The rod 32 may extend freely through the opening 34 in the top 22 and through a corresponding opening 35 in the follower plate 19, and may have its bottom end 36 freely pivoted in a similar aligned opening 37 in the plate 50 27 or in the bottom 6 of the device. A cotter pin or spring clip 38 at the top of the rod 32 and extending either through a hole therein or being held in notches therein, may serve to keep the rod in place. A transverse handle portion 39 of 55 the rod 32 serves to turn the shut-off disc 31. This will serve to prevent free dripping of grease when the device is not in use (when the grease is either one of inherently low viscosity or is rendered less viscous by high temperature). If desired also, a screw-threaded cap 40 may also be provided to be screwed into any of the sockets 10 when not in use.

In Figure 7, an alternative form of construction is shown in which a thin, weak, leaf-spring 65 41 is secured beneath the opening 7 at one end thereof, as at the point 42, so as to act as a weak spring check valve to minimize free dripping or drainage of grease when the device is not 70 in use. The spring 41 is shown in the drawings of a comparative thickness greater than what it would normally have, but this is done merely for purposes of illustration and for the greater convenience in showing the spring in place. 75

In Figures 9 and 10 a semi-circular shut-off disc 43 is shown, carried by and secured to a pivot pin 44 having a slot 45 in its outer end, for receiving a screw-driver or any thin flat object. 5 The shut-off disc 43 may be held in place by means of the pivot pin in any one of the forms of socket shown, as for instance by being fastened to the gasket-supporting member 29. By turning the disc 43 by means of the screw-driver or any thin flat object, the disc 43 can be brought over the opening 46 in the gasket-supporting member 29 so as to shut off the free flow of grease and can then again be turned away to permit the free flow. 10

15 Any of the shut-off means herein shown may be used whenever grease of a more or less fluid character is used or in climates where grease tends to become more fluid or less viscous.

In Figure 11, a modified form of construction 20 is shown wherein a small top portion of the cylindrical body 5 is flared outwardly slightly as at 48, in the form of a truncated cone, but preferably only at a very slight angle as generally indicated. 25

25 The follower plate 19 may be secured to the lid 22 by means of the screw 24 in the manner indicated in Figure 11. Thus, in this phase of the present invention, the raised portion 23 of the lid 22 may be offset in respect to the center of the lid. The follower 19 may be provided with a similar raised portion 49 either centrally, or offset as in Figure 11; which may be provided with a screw-threaded opening into which the end of the screw 24 may be threaded for holding the follower tightly against the lid 22 while in transit or storage. A small flanged disc 50 may be frictionally pressed into the raised portion 49 of the follower piston 19, so as to close the space and to prevent venting through the screw-threaded 30 opening therein and so as also to produce a generally continuous flat bottom for the follower piston 19. 40

By the means hereinabove last described and shown in the accompanying drawings hereinabove 45 referred to, the follower plate 19 may be held tightly against the friction top or lid 22, during shipment or storage of the can or drum of grease, so that if the drum is laid on its side or turned upside down, the grease will not get behind the follower-plate or piston 19. When it is desired 50 to use the drum of grease, it is merely necessary to set up the drum of grease in vertical position with its top up, as in Figure 11, and to unscrew the screw 24, so as to drop the follower piston or 55 plate 19 onto the top surface 51 of the grease. The container is not filled entirely with grease but an empty space is left at the top from about the point where the side-wall 5 starts to flare outwardly. 60

60 The follower piston or plate 19, thus released by unscrewing the screw 24 rests flat on the top of the body of grease and gradually adjusts or centers itself into the cylindrical body 5.

65 While the disc 50 closes up what would otherwise be a vent opening in the follower-plate or piston 19, yet the friction cover or lid 22 becomes vented through the opening through which the screw 24 passes (that is, just as soon as the screw 70 24 is unscrewed). For this reason, the entire original package of grease, in the form of a drum, may be used without ever substantially uncovering the grease and without ever doing anything more than unscrewing the screw 24 and then 75 repeatedly applying the suctional reservoir por-

tion or barrel of the grease gun or the like to the socket 10 thereof.

By reason of the outward flaring at 48, the grease-dispensing device of this embodiment of the present invention may also be stacked in vertical groups, that is, one on top of the other, because the bottom of one will fit into the top of the one beneath it. By reason of the fact that the raised portion 23 is offset from the center, it will not interfere with the downwardly extending conduit 9 at the bottom of the drum above it. 10

I may also provide bushings such as that shown in Figures 16 and 17 and also shown in Figure 11, for adapting a socket 10 of one predetermined size, to any one of a variety of different sizes of 15 grease-gun barrels or the like.

Thus, as the re-fill ends 16 of the cylindrical grease reservoirs or barrels 18 of grease guns vary both in diameter as well as in size of thread and the location of the thread, that is, internal and external, bushings 56 and 57 are provided, each having a thread 58 for exerting or for coating with the gun-receiving socket 10 of the grease-dispensing container and having another thread, as for instance, the internal thread 59 or the external thread 60, for receiving the refill end of the cylindrical grease reservoir or barrel 18 of the grease gun. Either of these two adapters 56 and 57 is provided with external means such as the knurled or serrated flange or spoked flange 30 61, whereby the adapter may be readily applied to the gun-receiving socket 10 or removed therefrom. 25

The adapter 56 is adapted for the barrels 18 35 of grease guns having a smaller external thread than what would correspond to the internal thread of the socket 10, while the adapter 57 is for barrels 18 of grease guns having external threads at the re-fill ends thereof. Each of the adapters 56 and 57 is provided with means for 40 receiving and retaining a sealing gasket 62, said means including an axial supporting surface and also a radial supporting surface as indicated in the drawings.

In Figures 12, 13, 14 and 15, a modified form 45 of follower piston construction is shown, wherein the upturned flange portion 52, which corresponds to the flange 20 hereinabove described, is notched at points uniformly spaced around its periphery as at 53, and wherein the upturned 50 portion 52 is turned up at a slight angle as for instance, about 15° (more or less). By making the follower plate or piston 19 of comparatively thin sheet metal, the portions 52 will be slightly 55 resilient in a radial direction.

In Figures 14 and 15, a modified form of construction is shown in which still thinner leaf-spring portions 54 are either spot-welded or riveted to the disc 19 for the same purpose.

By spacing the members 54 more or less closely 60 and uniformly around the circumference, and making them out of sufficiently thin spring metal, in relation to the comparatively thicker metal of the disc 19, a contact may be maintained with the cylindrical side wall 5 of the grease drum 65 even though the grease drum may occasionally be slightly dented and at the same time the grease is wiped down the sides of the grease drum as the follower plate passes down as the grease is emptied. 70

The forms of construction last above described also help to prevent the follower plate or piston from sinking down into the grease when standing idly, as the portions 52 and 54 will contact the edge of the cylindrical container 5 and will 75

tend to prevent the grease from working up around the edges.

The modified form of construction shown in Figures 12 to 15, inclusive, while especially useful in the device shown in Figures 1, 8 and 11, may also be incorporated in follower plates or follower pistons of the type shown in Patents Nos. 1,981,495 and 2,083,590.

By reason of its relatively loose fit or by reason of the resiliency of the members 52 and 54, and by reason of the relatively small axial dimension of the flanges 20, 52 and 54 thereof, the follower plate or piston 19 may pass any slight dents in the side-wall 5 of the grease-dispensing device 5 by tilting or angling until it has passed the dent. Thus, as the side-walls of drums of grease are sometimes slightly dented during shipping or while being handled in storage or while in use, such indentations tend to interfere with the passage of the follower piston or plate 19. This interference is avoided (within limits of denting) by the aforesaid tilting of the plate 19.

If desired, instead of the second thread on the adapters of Figures 16 and 17, a bayonet catch 25 may be provided for receiving the re-fill ends of grease guns having bayonet-catch means at their suction-fill ends.

In Figures 18 to 20 inclusive, a modified form of construction is shown wherein the cylindrical side wall 5 of the lubricant-dispensing device is pressed out, as at 63, over a generally circular area to form a slightly protruding boss presenting a generally flat or plain circular surface 64 against which the pressed-metal gun-receiving socket 65 may be placed, having a similar plain flat butting surface 66. To this extent the gun-receiving socket 65 is unlike the sockets shown in Figures 1 to 10 inclusive. The pressed sheet-metal socket 65 may be provided with an aperture 67 which is similar to the aperture 14 in the sockets shown in Figures 1 to 10 inclusive, but has an outwardly extending flange portion 68 pressed out therefrom. The flange 68 is extended through a similar aperture 13 in the flat portion 64 of the boss 63 protruding from the side-wall 5 of the grease-dispensing device and is then flared or crimped over as at 69, to form an anchorage and also a crimped sealing junction between the side-wall 5 and the socket 65. If desired, any suitable gasket 70 may be interposed between the juxtaposed flat surfaces 64 and 66, so as to insure that the juncture of the two numbers will be fluid-tight. If desired, the boss 63 and the flat portion 66 of the gun-receiving socket 65 may be spot-welded together at a series of spots 71 surrounding the aperture 67. By this combination of a crimped or interfolded sealing seam between gun-receiving-socket and reservoir and spot-welded securement of gun-receiving-socket to reservoir (as indicated particularly in Figures 20 and 21), the crimped or interlapped sealing seam between the gun-receiving-socket and reservoir is substantially relieved of all external stress or strain incident to external impact on the gun-receiving-socket or on the reservoir, or incident to any slight bending or twisting or deformation of the side wall of the reservoir. Thus, in this phase of the present invention the spot-welded securement between gun-receiving-socket and reservoir takes all or substantially all the strain which would tend to separate or detach the socket from the reservoir, thereby relieving the interlapped or crimped sealing seam from this strain, and minimize, if not indeed eliminate the danger of loosening said crimped sealing

seam. In this manner the gun-receiving-socket may be supported on the reservoir with a crimped or interlapped sealing seam having a periphery much less than that of the gun-receiving-socket and therefore capable of defining a constricted 5 passageway or conduit between suction-receiving socket and reservoir of a cross-sectional area substantially less than the cross-sectional area of the suction-receiving socket, and indeed, even substantially less than one-half of the cross-sectional area of the suction-receiving-socket.

In this form of construction, the passageway 9 may be formed in a manner similar to that shown in Figures 4 to 10 inclusive, by pressing the channel 26 out of the bottom 6 and spot-welding the 15 top plate 27 over the channel 26 and also to the side-wall 5 of the device as at 72.

This form of construction eliminates the need for the gasket supporting member 29 shown in Figures 4, 6, 7, 8, 9 and 10, because the inner 20 wall of the gun-receiving socket is flat.

A closure member 73 may also be formed of sheet metal, as indicated in Figure 20, with a transverse channel 74 pressed outwardly therefrom to act as a finger grip by which the plug 25 can be screwed into the sockets 10 or 65 or unscrewed therefrom.

In Figure 23, a modified form of adapter is shown, for accommodating grease guns of larger diameter than that of the diameter of the socket. 30 This form of adapter is also preferably pressed out of sheet metal with the screw-threaded portion 75 adapted to screw into the sockets 10 or 65, with the inturned lateral flange 76 thereof adapted to press against the sealing gaskets 30 35 77 in the sockets 10 or 65 and with the outer cylindrical portion 78 of a larger diameter being internally threaded to receive the larger grease-gun barrel 18, and having a sealing gasket 79 resting against the flat transverse connecting 40 portion 80 intermediate the two cylindrical portions 75 and 78, against which the end of the grease-gun barrel 18 may seal.

By reason of the attachment or securement of the sockets 10 and 65 to the outer surface or 45 wall of the sheet-metal body 5, as for instance, by spot welding thereto or by an interlapped crimped seal at the opening at a point below the bottom 6, a firm support is given to the gun-receiving socket on the outside of the container 50 body and extending outwardly from the side wall thereof, without any obstruction on the inside of the container tending to interfere with the full travel of the follower plate 19 to the bottom 6. Thus, the follower plate 19 may pass downwardly 55 below the level of the uppermost point of the socket 10 or 65 without being interfered by such socket or by its supporting means.

The present invention may be embodied in other specific forms without departing from the spirit or essential attributes thereof, and it is therefore desired that the present embodiments be considered in all respects as illustrative and not restrictive, reference being had to the appended claims rather than to the foregoing description to indicate the scope of the invention.

Having thus described the invention, what is hereby claimed as new and desired to be secured by Letters Patent is:

1. A dispensing device suitable for filling grease guns and the like and suitable for use as an original vendable merchandizing package unit for containing more or less viscous greases and like fluids in transit and storage and for thereafter dispensing the same, comprising a gen- 70 75

generally upright sheet-metal reservoir body of generally uniform horizontal cross-sectional area throughout the major portion of its vertical extent, a sheet-metal bottom raised sufficiently above the lowermost extremity of said body to afford a space therebeneath for a lateral passageway, a free-floating piston-like follower operatively disposed within said generally upright body and capable of rectilinear co-axial 5 placement downwardly within said body without rotation relative thereto, sheet-metal top closure means crimped to the upper end of said body, an aperture through said sheet-metal bottom, spaced inwardly from the side-walls of said body, 10 a suction-receiving socket associated with the side-wall of said body, adapted telescopically to receive a suction-filling barrel of another dispensing device such as the suction-filling barrel of a grease gun or the like, and having means for 15 making a relatively fluid-tight seal therewith, and a lateral passageway operatively interconnecting said socket with said aperture in the bottom, having at least the major part of its transverse cross-section disposed beneath said bottom. 20

2. A dispensing device suitable for filling grease guns and the like and suitable for use as an original vendable merchandizing package unit for containing more or less viscous fluids in transit and storage and for thereafter dispensing the same, comprising a generally upright reservoir body of thin form-retaining sheet material, a bottom near the lower end of said body formed of a thin form-retaining sheet material, an aperture through the side wall of said body, 25 and an upwardly inclined suction-receiving socket associated with the side wall of said body and communicating with said aperture, adapted telescopically to receive a suction-filling barrel of another dispensing device such as the suction-filling barrel of a grease gun or the like, and having means for making a relatively fluid-tight seal therewith, whereby said barrel may be filled suctionally while in an upwardly inclined position. 30

3. A dispensing device suitable for filling grease guns and the like and suitable for use as an original vendable merchandizing package unit for containing more or less viscous fluids in transit and storage and for thereafter dispensing the same, comprising a generally upright reservoir body of thin form-retaining sheet material, a bottom near the lower end of said body formed of a thin form-retaining sheet material, an aperture through the side wall of said body, and an upwardly inclined suction-receiving socket 35 associated with the side wall of said body and communicating with said aperture, adapted telescopically to receive a suction-filling barrel of another dispensing device such as the suction-filling barrel of a grease gun or the like, and having means for making a relatively fluid-tight seal therewith, whereby said barrel may be filled suctionally while in an upwardly inclined position. 40

4. A dispensing device suitable for filling grease guns and the like and suitable for use as an original vendable merchandizing package unit for containing more or less viscous greases and like fluids in transit and storage and for thereafter dispensing the same, including a reservoir body having side-wall and bottom formed of thin, form-retaining sheet material, a suction-receiving socket associated with the side-wall of said 45 reservoir near the bottom thereof and disposed

generally exteriorly of said side-wall, a passageway extending through the side-wall of said reservoir and establishing communication between said suction-receiving socket and the interior of said reservoir, said passageway having an effective cross-sectional area substantially less than the cross-sectional area of said suction-receiving socket and sealing means in said suction-receiving socket for making a seal with the end portion of the suction-producing means which may 10 be applied to said socket. 5

5. A dispensing device suitable for filling grease guns and the like and suitable for use as an original vendable merchandizing package unit for containing more or less viscous greases and like fluids in transit and storage and for thereafter dispensing the same, including a reservoir body having side-wall and bottom formed of thin, form-retaining sheet-material, a follower adapted to travel on the top surface of the fluid content of said reservoir body and adapted to travel to the bottom thereof, a suction-receiving socket associated with the side-wall of said reservoir body near the bottom thereof in operative relation to said follower, and a constricted passageway extending through the side-wall of said reservoir body and establishing communication between said suction-receiving socket and the interior of said reservoir, said passageway having an effective cross-sectional area substantially less than the cross-sectional area of said suction-receiving socket. 20

6. A dispensing device suitable for filling grease guns and the like and suitable for use as an original vendable merchandizing package unit for containing more or less viscous greases and like fluids in transit and storage and for thereafter dispensing the same, including a reservoir body having side-wall and bottom formed of relatively thin and more or less form-retaining sheet-metal, a follower adapted to travel on the top surface of the fluid content of said reservoir body and adapted to travel to the bottom thereof, a suction-receiving socket associated with the side-wall of said reservoir body near the bottom thereof in operative relation to said follower, and a constricted elongated lateral conduit extending through the side-wall of said reservoir and disposed asymmetrically with respect to said suction-receiving socket and establishing communication between said suction-receiving socket and the interior of said reservoir, said passageway having an effective cross-sectional area substantially less than the cross-sectional area of said suction-receiving socket. 45

7. A dispensing device suitable for filling grease guns and the like and suitable for use as an original vendable merchandizing package unit for containing more or less viscous greases and like fluids in transit and storage and for thereafter dispensing the same, comprising a reservoir body including side-wall and bottom formed of thin, form-retaining sheet-material and having a top, a suction-receiving socket associated with the side-wall of said reservoir body near the bottom thereof, a passageway generally beneath the level of said bottom establishing communication between said suction-receiving socket and said reservoir, said passageway having a generally shallow cross-sectional contour, whose vertical dimension is less than the diameter of said suction-receiving socket. 60

8. A dispensing device suitable for filling grease guns and the like and suitable for use as an original vendable merchandizing package unit 70

- for containing more or less viscous greases and like fluids in transit and storage and for thereafter dispensing the same, comprising a reservoir body including side-wall and bottom formed of thin, form-retaining sheet-material, a suction-receiving socket associated with the side-wall of said reservoir body near the bottom thereof, and a passageway generally beneath said bottom pressed out of the bottom sheet and communicating with said socket, and a separate thin-sheet cover plate over a portion of said downwardly pressed-out passageway and with its marginal portions overlapping the adjacent upper surface of said bottom.
15. 9. A dispensing device suitable for filling grease guns and the like and suitable for use as an original vendable merchandising package unit for containing more or less viscous greases and like fluids in transit and storage and for thereafter dispensing the same, comprising a sheet-metal reservoir body including side-wall and bottom, an integral boss pressed outwardly from said side-wall in the zone of said bottom, a suction-receiving socket secured to said boss, and a passageway through said boss, forming fluid-communication between said suction-receiving socket and the interior of said reservoir and a follower within said reservoir operatively related to said suction-receiving socket and adapted to travel to the bottom.
20. 10. A dispensing device suitable for filling grease guns and the like and suitable for use as an original vendable merchandising package unit for containing more or less viscous greases and like fluids in transit and storage and for thereafter dispensing the same, comprising a sheet-metal reservoir body including side-wall and bottom, an integral boss pressed outwardly from said side-wall in the zone of said bottom, a suction-receiving socket secured to said boss, and a passageway through said boss, forming fluid-communication between said suction-receiving socket and the interior of said reservoir and a follower within said reservoir operatively related to said suction-receiving socket and adapted to travel to the bottom.
25. 35. 11. A dispensing device suitable for filling grease guns and the like and suitable for use as an original vendable merchandising package unit for containing more or less viscous greases and like fluids in transit and storage and for thereafter dispensing the same, comprising a sheet-metal reservoir body including side-wall and bottom, an integral boss pressed outwardly from said side-wall in the zone of said bottom, with a part thereof above and a part thereof below the level of said bottom, a follower-plate in said reservoir adapted to travel from top to bottom, a suction-receiving socket secured to said boss, and a passageway through said boss forming a communication between said socket and the interior of said reservoir.
40. 45. 12. A dispensing device suitable for filling grease guns and the like and suitable for use as an original vendable merchandising package unit for containing more or less viscous greases and like fluids in transit and storage and for thereafter dispensing the same, including a reservoir body having side-wall and bottom formed of thin, form-retaining sheet-material, a suction-receiving socket associated with said side-wall with a part thereof below the level of said bottom and with a part thereof above the level of said bottom, and a passageway through said bottom and through said side-wall, communication with the level of the bottom.
50. 55. 13. A dispensing device suitable for filling grease guns and the like and suitable for use as an original vendable merchandising package unit for containing more or less viscous greases and like fluids in transit and storage and for thereafter dispensing the same, comprising a reservoir body including side-wall and bottom formed of thin, form-retaining sheet-material, a suction-receiving socket near the bottom of said reservoir and a tubular conduit of a length at least as great as the diameter of said suction-receiving socket and disposed at least partly beneath the level of said bottom, operatively interconnecting said suction-receiving socket with the interior of said reservoir body and a follower within said reservoir operatively related to said suction-receiving socket and adapted to travel to the bottom.
55. 60. 14. A dispensing device suitable for filling grease guns and the like and suitable for use as an original vendable merchandising package unit for containing more or less viscous greases and like fluids in transit and storage and for thereafter dispensing the same, including a sheet-metal reservoir body having side-wall and bottom, a suction-receiving socket on the outside of said reservoir near the bottom thereof, a passageway from said socket to said reservoir; said suction-receiving socket being secured to said reservoir against relative displacement by fastening means in a zone spaced outwardly from said passageway and having a separate fluid-sealing connection therewith in the zone of said passageway.
65. 70. 15. A dispensing device suitable for filling grease guns and the like and suitable for use as an original vendable merchandising package unit for containing more or less viscous greases and like fluids in transit and storage and for thereafter dispensing the same, including a generally upright sheet-metal container body, a sheet-metal bottom near the lower end of said body, an outlet-opening in said body near the bottom thereof, a suction-receiving socket associated with the outside of said body at said outlet opening and having an interlapped crimped sealing seam therewith without any inward extension into the body above the bottom and without any obstruction to the free travel of a follower-plate to and into contact with the bottom and sealing means associated with said suction-receiving socket for sealing against the end portion of suction-producing means when received by said socket.
75. 80. 16. A dispensing device suitable for filling grease guns and the like and suitable for use as an original vendable merchandising package unit for containing more or less viscous fluids in transit and storage and for thereafter dispensing the same, comprising a generally upright sheet-metal body, a sheet metal bottom, a suction receiving socket on the outside of said generally upright body near the bottom thereof, a fluid-conducting passageway operatively connecting said socket with the interior of said upright body and an externally operable shut-off in said passageway and movable transversely thereof and sealing means associated with said suction-receiving socket for sealing against the end portion of suction-producing means when received by said socket.
85. 90. 17. A dispensing device suitable for filling grease guns and the like and suitable for use as an original vendable merchandising package unit for containing more or less viscous fluids in

transit and storage and for thereafter dispensing the same, comprising a generally upright sheet-metal body, a sheet metal bottom, a suction receiving socket on the outside of said generally upright body and near the bottom thereof, and an externally operable, pivotally mounted and rotatable shut-off disc in said socket and sealing means associated with said suction-receiving socket for sealing against the end portion 5 of suction-producing means when received by said socket.

18. A dispensing device suitable for filling grease guns and the like and suitable for use as an original vendable merchandising package unit 15 for containing more or less viscous fluids in transit and storage and for thereafter dispensing the same, comprising a generally upright sheet-metal body, a sheet metal bottom, a suction receiving socket on the outside of said generally upright body near the bottom thereof, a passageway operatively connecting said socket with the interior of said upright body, and a shut-off associated with said passageway and operable through said socket and sealing means 25 associated with said suction-receiving socket for sealing against the end portion of suction-producing means when received by said socket.

19. A dispensing device suitable for filling grease guns and the like and suitable for use as an original vendable merchandising package unit 30 for containing more or less viscous fluids in transit and storage and for thereafter dispensing the same, comprising a generally upright sheet-metal body, a sheet metal bottom, a suction receiving socket on the outside of said upright body near the bottom thereof, a passageway operatively connecting said socket with the interior of said body, and an externally operable pivotally mounted and rotatable shut-off disc disposed in operative relation to said passageway 40 and in coaxial relation to said socket and sealing means associated with said suction-receiving socket for sealing against the end portion of suction-producing means when received by said 45 socket.

20. A dispensing device suitable for filling grease guns and the like and suitable for use as an original vendable merchandising package unit 50 for containing more or less viscous fluids in transit and storage and for thereafter dispensing the same, comprising a generally upright sheet-metal body, a sheet metal bottom, a suction receiving socket associated with said body near said bottom, a passageway operatively connecting said socket with the interior of said body, and an externally operable pivotally mounted rotatable shut-off operatively associated with said passageway and disposed with its axis line passing through said socket and sealing means 55 associated with said suction-receiving socket for sealing against the end portion of suction-producing means when received by said socket.

21. A dispensing device suitable for filling grease guns and the like and suitable for use as an original vendable merchandising package unit 65 for containing more or less viscous greases and like fluids in transit and storage and for thereafter dispensing the same, comprising a generally upright body having a generally uniform horizontal cross-section throughout the major portion of its extent, and having an outwardly flared upper portion, a bottom near the lower end of said body, a flanged lid fitting telescopically onto the upper flared end of said body, the 70 innermost diameter of the flange of said lid be-

ing of a diameter sufficiently greater than the diameter of the major extent of the body, so that the lid of one dispensing device may telescopically receive the lower end of the body of another like dispensing device of the same size 5 without substantially reducing the diameter of the lower end of the body.

22. A dispensing device suitable for filling grease guns and the like and suitable for use as an original vendable merchandising package unit 10 for containing more or less viscous greases and like fluids in transit and storage and for thereafter dispensing the same, comprising a container having a lid and having an outlet passageway near the bottom thereof, a socket operatively 15 connected with said outlet passageway, and a vent opening extending through said lid and a generally annular elevated shielding portion surrounding said vent opening pressed out of said lid.

23. A dispensing device suitable for filling 20 grease guns and the like and suitable for use as an original vendable merchandising package unit for containing more or less viscous greases and like fluids in transit and storage and for thereafter dispensing the same, including a reservoir 25 body having side-wall and bottom formed of relatively thin and more or less form-retaining sheet steel, a generally free-floating follower-plate disposed within said reservoir and adapted to rest on the top of the fluid content thereof, a suction-receiving socket associated with the side-wall of said reservoir near the bottom thereof and disposed generally exteriorly of said side-wall, a passageway extending through the side-wall of 30 said reservoir and establishing communication 35 between said suction-receiving socket and the interior of said reservoir, said passageway having an effective cross-sectional area substantially less than the cross-sectional area of said suction-receiving socket, and sealing means in said suction-receiving socket for making a seal with the end portion of the suction-producing means 40 which may be applied to said socket.

24. A dispensing device suitable for filling 45 grease guns and the like and suitable for use as an original vendable merchandising package unit for containing more or less viscous greases and like fluids in transit and storage and for thereafter dispensing the same, including a reservoir 50 body having side-wall and bottom formed of relatively thin and more or less form-retaining sheet material and having a top, a follower adapted to travel on the top surface of the fluid content of said reservoir and adapted to travel toward the bottom thereof, a suction-receiving socket associated with the side wall of said reservoir body near the bottom thereof in operative relation to said follower, a passageway generally beneath the level of said bottom establishing communication 55 between said suction-receiving socket and said reservoir, said passageway having a generally shallow cross-sectional contour whose vertical dimension is substantially less than the diameter of said suction-receiving socket.

25. A dispensing device suitable for filling 60 grease guns and the like and suitable for use as an original vendable merchandising package unit for containing more or less viscous greases and the like in transit and storage and for thereafter dispensing the same, comprising a generally upright reservoir body having side-wall and bottom formed of relatively thin and more or less form-retaining sheet metal and having a top forming therewith a generally completely closed reservoir, 70 a suction receiving socket on the exterior side 75

- 5 wall of said reservoir, an elongated conduit extending from a point near the center zone of the bottom of said reservoir to said socket and having communication therewith, said conduit having an effective cross-sectional area substantially less than the cross-sectional area of said suction-receiving socket, and sealing means in said suction-receiving socket for making a seal with the end portion of the suction-producing 10 means which may be applied to said socket.
- 10 26. A dispensing device suitable for filling grease guns and the like and suitable for use as an original vendable merchandising package unit for containing more or less viscous greases and 15 like fluids in transit and storage and for thereafter dispensing the same, including a generally upright reservoir body having side-wall and bot-

tom formed of relatively thin and more or less form-retaining sheet-metal and having a top, all forming a generally closed reservoir, a suction-receiving socket mounted on an exterior wall of said reservoir secured thereto against relative displacement, a generally elongated conduit extending from within said reservoir at a point near the center zone of the bottom thereof to said socket and having communication with said socket, said suction-receiving socket being secured to said reservoir against relative displacement by fastening means in a zone spaced outwardly from the juncture of said conduit and socket and having a separate fluid-sealing connection therewith in the zone of said juncture. 10 15
